UNITED STATES PATENT OFFICE.

JUAN MANUEL SANCHEZ FONTECHA, OF MEXICO, MEXICO, ASSIGNOR TO COMPAÑIA EXPLOTADORA DE LOS INVENTOS JULIA S. A., OF MEXICO, MEXICO.

SAFETY DEVICE FOR ELECTRIC-CURRENT MACHINERY.

1,035,563.

Specification of Letters Patent. Patented Aug. 13, 1912.

Application filed October 11, 1911. Serial No. 654,144.

To all whom it may concern:

Be it known that I, JUAN MANUEL SANCHEZ FONTECHA, subject of the King of Spain, residing at Mexico city, Mexico, have 5 invented a new and useful Improvement in Safety Devices for Electric-Current Machinery, of which the following is a specification.

This invention relates to improvements in 10 electric switches.

The object of the invention is to provide in a switch a simple and reliable arrangement of parts and for protecting from injury motors or other electrical appliances 15 in monophase or polyphase circuits.

In the accompanying drawings, Figure 1 is a diagram illustrating the application of my invention. Fig. 2 is a detail perspective of the improved switch.

20 The numeral 20 indicates a slab of marble, slate or other suitable material. On this slab are three switches 3, 3, 3 connected by wires 1, 1', 1''. As shown in the drawing three switches are controlled by a single 25 operating switch lever 5. The switches are exactly alike, and a description of one will be sufficient to an understanding of them all.

Each switch comprises a plate 6 having a main forwardly extended portion 7, and a 30 rearwardly extended portion 8, and an auxiliary rearwardly extended member 9. Extending upwardly from the plate 6, are two blades 10, located adjacent the end of the auxiliary member 9. A second rearwardly 35 extended auxiliary member 11 branches from the main rearwardly extended portion 8, and adjacent this member 11, and projecting upwardly from the plate 6 are two blades 12, which are of greater height than 40 the blades 10. To the end of the rearwardly extended main portion 8 is pivoted one leg of a switch lever 5, designed to coöperate with the blades 10 and 12.

Near one end of the base 20, is a bar 13. 45 A fuse 14, connects the terminal of the rearwardly extended auxiliary member 11, and the end of the bar 13. Connecting the end of the rearwardly extended auxiliary mem-

ber 9, and the bar 13, is a fuse 15, the resistance of which is considerably less than 50 that of the fuse 14. Extending from the bar 13, is a wire 16, connected to a motor 17.

The switch lever 5, has three legs to coöperate with the blades on each switch, and from the bar 13, of each of the switches a 55 wire 16 leads to the motor.

In operation, when the switch lever 5 is turned down the legs, first contact with the blades 12, and the current passes through the auxiliary members 11, and the stronger 60 fuses 14, and to the motor. Upon further rocking of the switch lever, the legs contact with the blades 10, and break contact with the upper ends of the blades 12. After the switch lever is completely lowered and contact is made with the blades 10, the current passes from the plates 6, auxiliary members 9, and the fuses 15, and thence to the motor. 65

After having thus described my invention, I claim the following:

The combination of a base, a pair of spaced apart blades connected to a plate on the base and having a main forwardly extended portion and a main rearwardly extended portion and an auxiliary rearwardly 75 extended member, a second larger pair of blades mounted on the main rearwardly extended portion, a second rearwardly extended auxiliary member branching from the main rearwardly extended portion opposite 80 the second larger pair of blades, a switch blade pivoted to the main rearwardly extended portion and adapted to be rocked to engage between the two sets of blades, a bar mounted on the base, a fuse connecting 85 the second rearwardly extended member and the bar, and a second fuse of less resistance than the before mentioned fuse connecting the first mentioned auxiliary rearwardly extended member and the said bar. 90

In testimony whereof, I affix my signature in presence of two witnesses.

JUAN MANUEL SANCHEZ FONTECHA.
